ROBERT M. MANNING, OF MEXIA, TEXAS.

OIL TANK.

Application filed November 5, 1926. Serial No. 146,488.

Oil field tanks are usually employed with an opening normally closed by a pivoted cover, and which opening is provided for the purpose of inspecting and measuring the 5 contents of the tank from time to time, use being made of a suitable measuring instrument which is inserted into the tank subsequent to the opening of said cover.

It is the purpose of the present invention 10 to provide an improved cover for said opening, and to associate therewith means for supporting the cover horizontally in an open position, in which position the cover can be employed as a support for the measuring 15 instrument, to allow the oil to drain from the measuring instrument onto the cover, which is designed to collect the oil and return it to the tank as the cover is closed.

The nature and advantages of the invention 20 will be better understood when the following detail description is read in connection with the accompanying drawing, the invention residing in the construction, combination and arrangement of parts as 25 claimed.

In the drawing forming part of this application like numerals of reference indicate similar parts in the several views and wherein:

30 Figure 1 is a fragmentary view of a tank showing the cover supported horizontally in opened position, and the measuring instrument arranged thereon.

Figure 2 is a fragmentary sectional view 35 showing the cover closed.

Figure 3 is a fragmentary sectional view of the neck of the tank.

Figure 4 is a sectional view through the 40 cover.

45 Referring to the drawing in detail 10 represents a portion of an oil field tank which has bolted or otherwise suitably secured thereto a neck portion 11 which communicates with the tank, and through which neck portion the tank is inspected from time to time and the contents measured by what is commonly known as a thief, which is adapted to be inserted within the tank through the neck portion, subsequent to the opening 50 of the cover 13 therefor. This cover is provided with a bracket arm 14 which is pivoted to a similar arm 14' in a manner to permit the cover to be swung to an open position wholly to one side of the neck portion, when it is desired to inspect or measure the 55 contents of the tank 10. A gasket 16 is se-

cured to the flange 15 formed on the neck, to provide a fluid-tight connection between the tank and cover when the latter is closed. The cover is effectively held in its closed position by means of a pivotally mounted bolt 60 17 adapted to be received between spaced lugs 18 projecting from the cover, and to be subsequently engaged by a wing nut 19 threaded on the bolt. 65

In accordance with the present invention the cover 13 is provided with an annular rim or flange 20 to prevent the drippings from the thief from running off of the cover, when the latter is employed as a support for the 70 thief in the manner illustrated in Figure 1. While any suitable means may be employed for the purpose of supporting the cover horizontally in an opened position, so that it may be used as a support for the thief, I 75

preferably provide the cover with a substantially U-shaped member 21 which constitutes a handle to facilitate opening or closing of the cover, and is also used in the capacity of a support for the cover when the latter is 80 opened. In other words when the cover is swung to an opened position, the U-shaped member 21 repose upon the top of the tank, thereby supporting the cover horizontally 85 for use as a support for the thief. The latter when arranged on the cover is therefore allowed to drain, and the oil falling upon the cover is subsequently emptied into the tank when the cover is closed. For this purpose the cover is provided with a metallic plate 90

22 supported by the rim or flange 20, the plate 22 being spaced from the adjacent side of the cover 13 to provide a pocket 23 into which the oil runs to its closed position. The plate 22 may vary in size and shape without departing from the spirit of the invention. Obviously the plate prevents the oil from leaving the cover while the latter is being closed, and as the pocket is arranged next to the hinge or pivot connection for the cover, 100 it will be manifest that the oil remains within the pocket 23 until the cover is finally closed. The oil will then empty into the tank 10, for which purpose the plate is slightly trough-shaped as clearly illustrated 105 in Figure 4.

While it is believed that from the foregoing description, the nature and advantages of the invention will be readily apparent, I 110 desire to have it understood, that I do not limit myself to what is herein shown and described and that such changes may be re-

sorted to when desired as fall within the scope of what is claimed.

What is claimed is:

1. In combination, a tank having a neck portion, a pivoted cover therefor adapted to be swung wholly to one side of the neck to an opened position, an annular rim projecting from the underside of the cover, and a plate secured to said annular rim in spaced relation to the cover to form a pocket to receive a liquid when the cover is swung to its closed position, said plate being curved transversely to guide and return the liquid into the tank as the cover is closed.
2. In combination, a tank having a neck portion, a pivoted cover therefor adapted to

be swung wholly to one side of the neck to an opened position, means carried by the cover and adapted to repose upon the tank to support the cover horizontally in its opened position, an annular rim projecting from the underside of the cover, a segmental plate secured to said rim and spaced from the underside of the cover to form a pocket by the intervening space adapted to receive a liquid as the cover is swung to a closed position, and said plate being curved to form a trough to guide the liquid into the tank as the cover is closed.

In testimony whereof I affix my signature.

ROBERT M. MANNING.
